UNITED STATES PATENT OFFICE.

GEORGE W. ATHERTON, OF LIVERMORE, KENTUCKY.

CONVERTIBLE DRYING KILN AND CRIB.

Application filed July 29, 1921. Serial No. 488,399.

To all whom it may concern:

Be it known that I, GEORGE WILLIAM ATHERTON, a citizen of the United States, and a resident of Livermore, in the county 5 of McLean and State of Kentucky, have invented certain new and useful Improvements in Convertible Drying Kilns and Cribs, of which the following is a specification.

10 My invention relates to a convertible drying kiln and crib for corn or other grain and has for its object to provide a structure of this character constituted entirely of cement and steel so as to be fire proof, lightning proof and rat proof, and which is adapted to efficiently operate to dry corn too succulent or sappy for storage or to be readily converted into a crib for receiving and storing corn or other grain.

15 Other objects and advantages of the invention reside in certain novel features of construction, combination and arrangement of parts which will be hereinafter more fully described and particularly pointed 20 out in the appended claims, reference being had to the accompanying drawings forming part of this specification, and in which:

25 Figure 1 is a side elevational view illustrating the preferred embodiment of the invention;

30 Figure 2 is a view thereof in transverse vertical section;

Figure 3 is a view in transverse horizontal section;

35 Figure 4 is a perspective view illustrating the shaft; and

Figure 5 is a fragmentary perspective view illustrating one of the ventilating openings and its shutter.

40 Referring to the drawings wherein for the sake of illustration is shown the preferred embodiment of the invention, the numeral 10 designates the base upon which the cylindrical body 11 of the convertible drying kiln and crib is arranged. The cylindrical body 11 is preferably constructed 45 of concrete and is provided with a door 12. An imperforate bottom wall 13 closes the lower end of the cylindrical body and is preferably integral therewith, the upper end of the cylindrical body being closed by a sloping roof 14 having a central opening 15 provided therein.

50 Ventilating openings 16 are provided in the cylindrical body portion and preferably are arranged in circumferential series, each

circumferential series being spaced vertically from the other series. Steel screening 17 extends across the openings at the inner ends thereof and at the outer ends of the 60 openings swinging shutters 18 are arranged, the shutters being pivotally connected to the body portion and being imperforate so that when they are closed they prevent flow of air through the openings 16. 65

A slatted floor 20 is arranged within the body 11 adjacent the lower end thereof but spaced from the bottom wall 13 so as to define with the bottom wall a heat distributing chamber or space 21. A central 70 shaft designated generally at 22 rests at its lower end upon the slatted floor and extends axially of the body 11 and through the central opening 15 of the roof. The shaft comprises a plurality of spaced longitudinal 75 bars 23 arranged in circular series and secured in position by means of flat rings 24 connected with each of the bars by a suitable fastening means 25. A cap plate 26 is associated with the upper end of the 80 shaft 22 and includes a depending annular flange 27 fitted down around the bars 23 which go to make up the shaft and secured to these bars by fastening means 27a. At the intersection of the shaft and roof, a circular band 28 embraces the shaft 22 and has its lower end abutting the roof. The band 28 is secured in this position by suitable fastening means and preferably the fastening means 25 which secure the flat 85 rings to the bars of the shaft are also utilized for this purpose. Screening 29 which may comprise reticulated steel fabric completely encloses the portion of the shaft 22 projecting above the roof, the screening 90 extending from the annular flange of the cap plate to the circular band 28.

A plurality of bridge bars or slats 30 are arranged within the cylindrical body 11 and extend longitudinally thereof. These 100 bridge bars are arranged as shown in Figure 3, one being arranged along each side of each of the ventilating openings and others being arranged intermediate certain of these openings. The bridge bars are preferably 105 constructed of metal and are attached to the body portion 11 by means of attaching brackets 31.

A heating chamber 35 having a door 36 is arranged to one side of the cylindrical 110 body and below the floor 13 thereof and a heater 37 is arranged in the heating chamber

35. An offtake pipe 38 leads from the heater through an imperforate partition 39 which extends across the lower end of a flue 40 extending vertically and along side of 5 the cylindrical body portion 11. A heating duct 42 leads from the heater 37 to the heat distributing space 21. The partition 39 serves to prevent the products of combustion from finding their way into the crib or hollow body 11 and also constrains the heated air to flow through the duct 42 and through the hollow body and shaft.

In operation when it is desired to use the apparatus as a drying kiln for extremely 15 succulent or sappy corn or other grain the shutters 18 as well as the door 12 are closed and the heater 37 is started. The heater furnishes the supply of heat to the heat distributing space 21 by means of the heating 20 duct 42 and from the heat distributing space the heat rises through the slatted floor 20 and is uniformly distributed throughout the grain arranged in the cylindrical body portion 11 drying the grain to the desired 25 degree. When it is desired to use the apparatus as a corn-crib for storing or preserving corn or other grain the heater 37 is rendered idle and the shutters 18 are opened. This being the case, there is a circulation of 30 air through the grain so that the grain is thoroughly ventilated so as to preserve it in desired condition. It is to be noted that the bridge bars 30 serve to prevent the grain from wedging or packing in or against the 35 screening of the ventilating openings there-

by insuring a free ingress of air into the cylindrical portion.

I claim:

1. In an apparatus of the character described, a body having an imperforate bottom wall, said body having a plurality of screened ventilating openings, a roof having an opening, a shaft extending through the body and the opening of the roof, and bridge bars arranged within the body and 40 extending longitudinally thereof adjacent said ventilating openings.

2. In an apparatus of the character described, a hollow body having an imperforate bottom, a floor spaced from the bottom and having openings therein and defining with the bottom a heat distributing chamber, said hollow body having a plurality of screened ventilating openings 50 provided with closures, a roof having a central opening, a shaft extending through the body and through the central opening of the roof, the lower end of the shaft resting on the floor and said shaft comprising longitudinal bars, a ring secured to the bars for 55 maintaining them in proper position, a cap plate on the upper end of the shaft, a band encircling the shaft and abutting the roof at the intersection of the shaft and roof and screening extending around the shaft between the cap plate and the band, and means for supplying heat to the heat distributing chamber.

GEORGE W. ATHERTON.
